SERVICE SIGNAL FOR TABLES

Austin E. Myers, Amarillo, Tex.

Application April 7, 1949, Serial No. 86,095

1 Claim. (Cl. 116—132)

1

This invention relates to improvements in service signals, such as those used on tables in restaurants for attracting the waiter's attention when the customer wants service.

An object of the invention is to provide a simplified construction including a swinging pivoted arm, and so arranged that said arm will not likely strike other objects on the table.

Another object of the invention is to provide, in a service signal, an arrangement whereby the same may be projected outwardly from a booth of the type found in cafes.

Another object of the invention is to provide a service signal of the relatively long pivoted arm type for simplicity and economy of construction, yet one in which the arm extends vertically in operation for attracting the waiter's attention.

These and other objects of the invention will become apparent from the following description and the accompanying drawings, wherein:

Figure 1 is a perspective view of a service signal embodying the features of the present invention.

Figure 2 is a side elevation of the service signal illustrated in Figure 1, and showing the same arranged outwardly and vertically arranged relative to its base, and which arrangement is preferred when used in a booth whereby the signal may be projected beyond the outer end of the table in the booth.

Figure 3 is an enlarged elevation and broken sectional view of one side of the signal base and the lower end of the standard, and particularly illustrating the trigger mechanism for engaging the flag or signal at the outer end of the signal arm when the assembly is in its closed position.

Figure 4 is an end elevation of the pivot arrangement connecting the upper end of the standard with the lower end of the signal arm.

Figure 5 is a vertical sectional view taken on lines 5—5 of Figure 4, and showing a spring arrangement for raising the signal arm to a vertical position when the outer end of said arm is released by the trigger mechanism illustrated in Figure 3.

The numeral 1 designates a base in the form of a relatively heavy ashtray 2 having an integral lateral extension 3 at one side. A square socket 4 is formed through the extension 3 for detachably receiving a projection 5 at the lower end of an angularly disposed or inclined standard 6. The length of the upper edge of the standard 6 is slotted, as at 7, to receive an arm 8 which is pivoted at one end by a pin 9 extending through the upper end of said standard 6. The closed

2

position of the arm 8 is shown by means of dotted lines in Figure 1. The end of the arm 8 opposite the pivot pin 9 is provided with an integral disc or flag 10, and when the device is in its closed position said flag is received substantially within an enlarged portion 11 in the lower end of the standard 6. The slot 7 extends through the enlarged portion 11 and is shaped at its lower end, as shown in Figure 3, to receive the contour of the flag 10.

A trigger mechanism 12 is provided in the lower end of the standard 6 and is received within a lateral opening 13 above the projection 5. The trigger mechanism 12 is comprised of a leaf spring 14 held against the upper surface of the opening 13 by means of a screw 15. The end of the spring 14 opposite the screw 15 projects outwardly from the standard 6 to provide an actuating button 16. The spring 14 is upwardly and angularly formed intermediate its ends to provide a latch 17 for engagement with a notch 18 in the outer end of the flag 10.

A spring 19, as particularly shown in Figures 4 and 5, is received within opposing notches 20 in the upper end of the standard slot 7. The ends of the spring 19 are coiled about the pivot pin 9, and their projecting ends contact the sides of the notches 20, as shown in Figure 5. The center portion of the spring 19 extends outwardly from the pin 9 where it engages one edge of the signal arm 8; and the spring 19 is arranged for raising the said arm when the flag 10 is released by the trigger mechanism 12. A shoulder 21 on the pivot end of the arm 8 engages a shoulder 22 in the upper end of the standard 6 for maintaining the arm 8 in a vertical position when the flag 10 is released.

By reason of the described angular or inclined disposition of the standard 6, and by reason of the arcuate movement of the arm 8 thereabove, the flag 10 is not likely to strike objects on the table when the signal is operated. The standard 6 may be positioned above the ashtray 2 so as to occupy very little space on the table. When the device is used in a booth, the standard 6 is arranged outwardly relative to the ashtray 2 and is placed on the outer end of the booth table.

Normally, the signal is maintained in its closed position with the flag 10 received within the enlarged portion 11. By depressing the trigger button 16, the flag 10 is released and the arm 8 raises the same to a vertical position for attracting the attention of the waiter. The device is closed by manually lowering the arm 8, and whereupon the trigger mechanism 12 engages the

notch 18 in the flag 10 for maintaining the latter within the enlarged portion 11 of the standard 6.

The described form of the invention may be made in many ways within the scope of the appended claim.

What is claimed is:

A service signal for tables, comprising a relatively heavy round flat base having an integral extension on one side thereof, a square socket formed in the upper surface of said extension, a relatively long standard having a square projection on the lower end thereof adapted to be received within said socket, said projection being angularly disposed with respect to the length of said standard and whereby said standard will be inclined with respect to the vertical when said projection is positioned in said socket, an enlarged portion formed in the end of said standard near said projection, a slot in the upper edge of said standard and extending from the top thereof into said enlarged portion, a signal arm substantially as long as said standard and having one end thereof pivotally secured in the upper end of said slot by means of a pin passing

through said standard and said arm, an enlarged portion on the end of said arm opposite its pivoted end and adapted to be received within said enlarged portion in said standard, a trigger mounted within said enlarged portion and adapted to engage said enlarged end of said arm, and a wire spring coiled around said pin and having one end thereof engaged with said arm and having the remaining end thereof engaged with said standard.
